Primary Examiner — Kevin Rudzinski*(74) Attorney, Agent, or Firm* — Barnes & Thornburg LLP(57) **CLAIM**

I claim the ornamental design for an LED spot lamp, as shown and described.

DESCRIPTION

FIG. 1 is a front perspective view of a design of the LED spot lamp;

FIG. 2 is another front perspective view of the LED spot lamp of FIG. 1;

FIG. 3 is a front elevation view of the LED spot lamp of FIG. 1;

FIG. 4 is a rear elevation view of the LED spot lamp of FIG. 1;

FIG. 5 is a first side elevation view of the LED spot lamp of FIG. 1, with the second side elevation view being a mirror image of the first side elevation view; and,

FIG. 6 is a bottom plan view of the LED spot lamp of FIG. 1, with the top plan view being a mirror image of the bottom plan view.

The features shown in broken lines depict environmental subject matter only and form no part of the claimed design.
